Des. 181,232
Patented Oct. 15, 1957

181,232

CEMETERY MEMORIAL PLAQUE OR THE LIKE

Robert J. Rettman, Pittsburgh, Pa., assignor to Jas. H. Matthews & Co., Pittsburgh, Pa., a corporation of Pennsylvania

Application July 24, 1956, Serial No. 42,368

Term of patent 14 years

(Cl. D79—2)

Fig. 1

Fig. 2

I claim:

The ornamental design for a cemetery memorial plaque or the like, substantially as shown.
